HOUSING FOR MERCURY ARC LAMPS AND THE LIKE

Donald L. Jackson, Moundsville, W. Va., assignor to
Sylvania Electric Products Inc., a corporation of
Delaware

Filed Dec. 24, 1963, Ser. No. 77,915

Term of patent 14 years

(Cl. D48—20)

FIG.4

FIG.5

FIGURE 1 is a top plan view of a housing for mercury arc lamps and the like, showing my new design.

FIGURE 2 is a front elevational view thereof.

FIGURE 3 is an end elevational view thereof.

FIGURE 4 is a perspective view thereof.

FIGURE 5 is a sectional view thereof taken along the line 5-5 of FIGURE 1.

I claim:

The ornamental design for a housing for mercury arc lamps and the like, as shown.
